SHOCK RELIEF UNIT FOR CRUTCHES

Michael Shellhouse and Cecil E. Cleaver,
Gary, Ind.

Application October 15, 1946, Serial No. 703,388

5 Claims. (Cl. 135—53)

1

This invention relates to improvements in crutches.

In the usual or ordinary type of crutch there is found, secured between the lower ends of the side pieces forming the crutch frame, a solid post of wood which carries a rubber or rubber and fabric tip upon its lower end. In using a crutch of this character the user is continually subjected to jars due to the insufficient resiliency of the rubber tip which is provided more for the purpose of preventing the crutch from slipping than for relieving the user of jars.

The present invention has for its primary object to provide an improved crutch foot portion of a yieldable character designed to absorb shock incident to the use of the crutch and thereby make its use more comfortable.

A further and more specific object of the invention is to provide a foot piece or unit for a crutch, including a fixed cylinder and a movable piston in the cylinder, upon the lower end of which piston a friction tip is mounted. Within the cylinder a yieldable unit in the form of a coil spring normally urges movement of the piston outwardly and the inward movement of the piston in the cylinder is yieldingly resisted both by the coil spring and by compressed air which is permitted to escape slowly through a control valve. Accordingly the device of the present invention provides a foot piece by which there is obtained an air cushion which makes possible the use of the crutch without subjecting the user to shocks and jars as in the ordinary type of crutch structure.

Another object of the invention is to provide an air cushion shock relief unit or foot piece for a crutch which is of relatively simple construction and which may be readily substituted for the present solid post foot piece.

The invention will be best understood from a consideration of the following detailed description taken in connection with the accompanying drawing forming a part of the specification with the understanding, however, that the invention is not confined to a strict conformity with the showing of the drawing but may be changed or modified so long as such changes or modifications mark no material departure from the salient features of the invention as expressed in the appended claims.

In the drawing:

Figure 1 is a view in elevation of a unit constructed in accordance with the present invention, showing the same mounted between the lower ends of the side portions of a crutch frame, the lower part of the unit piston being broken away.

Figure 2 is a longitudinal section taken substantially on the line 2—2 of Figure 1.

Figure 3 is an enlarged detail showing the air admission and exhaust valves.

Figure 4 is a transverse section taken substantially on the line 4—4 of Figure 1.

Referring now more particularly to the drawing there are shown in Figure 1 the lower ends of the two side portions of a crutch frame, such ends of the frame being designated 10.

In accordance with the present invention there is provided a relatively long cylinder 11 of an outside diameter to fit snugly between the crutch frame portions 10, in the manner illustrated. The lower end of this cylinder 11 has the wall thickened slightly as indicated at 12, throughout a portion of the length of the cylinder, thereby providing the flange or shoulder 13 upon which rests a flat washer or collar 14. The lower ends of the frame portions 10 rest upon this collar 14 and the opposite sides of the collar lying in a line perpendicular to the plane in which the portions 10 lie, are turned upwardly against the adjacent sides of the cylinder 11 as indicated at 14'.

Directly above the collar 14 a bolt 15 passes diametrically through the cylinder and the head 16 at one end of the bolt and the nut 17 threaded upon the other end, lie in suitable recesses 18 formed in the lower ends of the frame portions 10 as shown in Figures 1 and 4.

The bolt 15 maintains in position and limits the inward and outward movements of the tubular piston 19 which extends into the open end of the cylinder and has snug contact with the inner wall thereof as shown in Figure 2. This function of the bolt 15 is performed by providing the upper end of the piston 19, at opposite sides, with the longitudinal guide slots 20 through which the bolt 15 passes.

The lower end of the piston 19 is closed as indicated at 21 and is designed to have fixed thereon an anti-skid tip 22 of the type commonly employed upon crutches.

The inner and upper end of the piston 19 is closed by the plug 23 and this has secured to the top surface thereof, by means of the cap screw 24 and the plate or disk 25, the cup washer 26 which bears against the inner wall surface of the cylinder 11 to prevent the escape of air from the cylinder around the end of the piston, as the piston is driven inwardly.

50 The top end of the cylinder 11 is closed by the valve head 27. This head 27 has the central or axial bore 28 formed therethrough, the inner end portion of which bore is suitably constricted to form a ball valve seat 29 upon which rests 55 the ball check valve 30. The outer end portion of the bore 28 is of slightly enlarged diameter and is screwthreaded as indicated at 31 to receive the socket nut 32, through the center of which is formed a relatively small diameter air escape passage 33. Within the inner end of the bore 28

there is interposed between the ball check 30 and the nut 32, the spring 34 which constantly yieldingly presses the ball onto the seat 29 to close the inner end of the bore and thereby prevent the entrance of air into the cylinder upon the outward movement of the piston 19.

Within the cylinder 11 is a coil spring 35 which bears at its upper end against the under side of the head 27 and at its lower end against the disk 25. This spring 35 constantly urges the piston 19 outwardly to the limit of its movement as controlled by the bolt 15.

Fixed to the top of the valve head 27 is the substantially U-shaped clevis 36. This clevis has the upstanding side portions 37 and the intermediate connecting portion 38 which lies upon the top of the valve head 27 and which is provided with an opening 39 through which the socket nut 32 may be introduced into or withdrawn from position. The side portions 37 position against the inner sides of the portions 10 of the crutch frame and are provided with suitable apertures 40 to receive the securing bolts 41 which pass through the crutch frame side portions as shown in Figure 1. Thus the upper end of the cylinder 11 is firmly secured in place and the lower ends of the portions 10 of the frame rest upon the collar 14 which in turn rests upon the shoulder 13 of the cylinder thereby providing a firm and safe support for the frame on the foot assembly.

Adjacent to the upper end of the cylinder 11 there is provided an air intake port 42 and this is covered by a valve unit which is generally designated 43 and which comprises a hollow shell 44 having an air inlet opening 45, and a suitable air control valve assembly 46 positioned in the shell. This assembly consists of a seat plate *a* having an opening *b* over which lies the valve disk *c*. A cap *d* covers the inner side of the plate *a* and has the inner air openings *e*. The disk *c* is pressed to its seat over the opening *b* by the spring *f*. By this means air passes into the cylinder by way of the openings 42 and 45 and *e* upon outward movement of the piston. While any suitable type of valve assembly may be used in the shell 44 preference is had for a valve of the form used in fuel pumps of a well-known make and which are of the construction here shown and described.

From the foregoing it will be readily apparent that there is provided in the present invention a novel crutch foot unit which provides a yieldable cushion support for the crutch to give the maximum degree of comfort in connection with its use.

We claim:

1. The combination with a crutch having a frame provided with spaced parallel lower end portions, of a cushion foot unit comprising a cylinder interposed between said end portions, a substantially U-shaped clevis secured to an end of the cylinder and having spaced side portions secured to the adjacent portions of the frame, a collar encircling the cylinder and having the lower ends of the frame portions resting thereon, a piston slidably in the cylinder and having an end extending downwardly therefrom, a ground engaging tip at the outer end of the piston, means within the cylinder normally urging movement of the piston outwardly, valve controlled air inlet and outlet ports for the cylinder, and means limiting the outward movement of the piston.

2. A crutch foot unit designed to be secured between the lower end portions of a crutch frame, comprising a cylinder, a valve head in one end

of the cylinder, an outwardly opening air exhaust port in said head, a substantially U-shaped clevis secured to the head and adapted to secure the end of the cylinder between adjacent side portions of the crutch frame, a piston slidably in the cylinder and extending from the other end thereof, resilient means normally urging the piston outwardly, means carried by the cylinder and having loose connection with the piston for limiting the inward and outward movement of the piston, a ground engaging tip at the outer end of the piston, and a valve controlled air intake port for the cylinder.

3. In a crutch structure having a frame terminating in spaced lower end portions, a cylinder positioned between and secured to said end portions of the frame, means carried by the cylinder against which the end portions bear, a piston within the cylinder and extending downwardly therefrom, a ground engaging tip at the outer end of the piston, a washer carried at the inner end of the piston and slidably engaging the inner wall of the cylinder, spring means within the cylinder normally urging movement of the piston outwardly, valve controlled air inlet and exhaust ports for the cylinder, a substantially U-shaped clevis secured to the inner end of the cylinder and having spaced side members positioned against the inner sides of the said frame portions, and means securing the said sides of the clevis to the adjacent portions of the frame.

4. In a crutch structure having a frame terminating in spaced lower end portions, a cylinder having a substantial part of its length positioned between said end portions of the frame, means connecting the cylinder with said end portions, said cylinder at its lower end being formed to provide an encircling shoulder, a flat collar encircling the cylinder above and resting upon said shoulder, the ends of said lower end portions resting upon said collar, the collar at opposite sides being turned up to bear against adjacent portions of the cylinder between the said end portions of the crutch frame, a piston slidably engaging in the cylinder and extending downwardly below the lower end thereof, a tip upon the lower end of the piston for engaging the ground, resilient means within the cylinder normally urging movement of the piston outwardly, an air inlet valve for the upper end of the cylinder, an air outlet bleed valve in the upper end of the cylinder, and means limiting the outward movement of the piston in the cylinder.

5. A crutch structure of the character stated in claim 4 wherein said movement limiting means for the piston comprises a bolt extending transversely through the cylinder immediately above the collar and having its ends housed in the lower end portions of the crutch structure, the piston being longitudinally slotted for the extension of the bolt therethrough.
